UNITED STATES PATENT OFFICE.

LEWIS T. HOWARD, OF SMITH'S MILLS, MISSISSIPPI.

IMPROVEMENT IN FEATHERING PADDLE-WHEELS.

Specification forming part of Letters Patent No. **16,589**, dated February 10, 1857.

To all whom it may concern:

Be it known that I, LEWIS T. HOWARD, of Smith's Mills, in the county of Carroll and State of Mississippi, have invented an Improvement in Paddle-Wheels; and I do hereby declare that the following is a full and exact description thereof, reference being had to the accompanying drawings, making a part of this specification.

Figure 1 is an outside end view of my improved propelling-wheel, together with a side view of the timbers of a vessel which support said wheel; Fig. 2, an inside view of said wheel, together with a view of its inner supporting-timbers; Fig. 3, a top view of said wheel and its supporting-timbers; and Fig. 4, a side view of the stationary governing-wheel E, with which the movements of the paddle-wheel are so combined as to retain the sides of all the paddles in vertical positions.

Similar letters indicate like parts in all the figures.

The paddles *ii* of the said propelling-wheel are secured in any proper manner to the paddle-shafts *mm*, and the said paddle-shafts are combined with the supporting-wheels *F G* in such a manner that they can be freely rotated in suitable bearing-boxes. Grooved rollers *ll* are placed upon the wrists of the cranks of the paddle-shafts *mm*, which rollers surround and embrace the periphery of the governing-wheel E, and the outer extremity of the said crank-wrists are all connected with each other by means of the flat bars *kk*. The crank-arms of the paddle-shafts *mm* being in line with the sides of the paddles and the governing-wheel E being secured in such a position as to bring its axis vertically over the axis of the shaft *H* of the paddle-wheel, it will be perceived that the sides of all the paddles must

at all times be retained in vertical positions.

To prevent the barrels of the grooved pulleys *ll* from coming in contact with the entire periphery of the governing-wheel E, and thereby producing a saving of friction, the upper and lower portions of the periphery of said governing-wheel may be slightly flattened, as shown in Fig. 4; but when the said governing-wheel is thus shaped the flanges of the grooved rollers *ll* should be of sufficient length to embrace every portion of the periphery of said wheel. It will thus be perceived that this manner of constructing propelling paddle-wheels enables the crank-arms of the paddle-shafts to be of a much greater length than they can be made when the governing-wheel E is so combined with the other parts of the paddle-wheel that it must rotate therewith and its weight be supported by the shaft of said wheel. The other advantages of my improved paddle-wheel over all others heretofore constructed are too apparent to require pointing out.

What I claim as my invention, and desire to secure by Letters Patent, is—

Connecting the cranks of the paddle-shafts with each other around and with the stationary governing-wheel E by means of the connecting-bars *kk* and the grooved rollers *ll* or their equivalents, substantially as herein set forth.

The above specification of my new and useful improvement in propelling paddle-wheels for steamboats signed and witnessed this 5th day of January, 1857.

LEWIS T. HOWARD.
